[57] CLAIM

We claim the ornamental design for a toothbrush package, as shown and described.

DESCRIPTION

FIG. 1 is a right front perspective view of a package for a toothbrush showing our new design;

FIG. 2 is a left front perspective view thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof; and,

FIG. 8 is a bottom plan view thereof.

The broken line showing in the drawing is for illustrative purpose only and forms no part of the claimed invention.
